UNITED STATES PATENT OFFICE.

HARRY B. ROWE, OF WILMINGTON, DELAWARE.

SMOKE-CONSUMER.

1,010,807.

Specification of Letters Patent. Patented Dec. 5, 1911.

Application filed January 25, 1911. Serial No. 604,564.

To all whom it may concern:

Be it known that I, HARRY B. ROWE, a citizen of the United States, residing at Wilmington, in the county of Newcastle and State of Delaware, have invented certain new and useful Improvements in Smoke-Consumers, of which the following is a specification, reference being had therein to the accompanying drawing.

This invention relates, in its broad idea, to a smoke consumer for use particularly in locomotives; although it may be employed with equal advantage in the fire boxes of stationary or marine boilers.

It is a well known fact that smoke is caused by poor combustion and insufficient air mixing with the gases from the burning fuel.

While I am aware that numerous devices have been employed with some success for supplying a greater amount of air to the fire box than is introduced therein by a natural draft; these devices, as a rule, have been faulty in that, being subjected to the intense heat of the fire box, they become burned out and useless within a short time; and also they detract from the heating surface of the fire box.

My present invention relates particularly to a novel construction and application of air jet pipes, or nozzles, and operating means for introducing a supply of heated air into the firebox to mix with the gases to produce a more perfect combustion, and thus consume the smoke.

The objects of the invention are to provide an air pipe or nozzle, that shall be cheap, durable and efficient; and easily installed in the fire box of any boiler, either locomotive, marine or stationary.

Another object of the invention is to provide a device of this class that shall be easily operated, and that is so constructed that it will withstand the heat to which it is subjected.

With these and other objects in view, my invention consists in certain construction and combination of parts as will hereinafter be fully described and claimed and illustrated in the accompanying drawings, which form a part of this application, and in which like figures of reference refer to corresponding parts in all of the views; but it is fully understood that while I have described my invention as shown in the draw-

ings, that I do not confine myself to the exact design, as slight changes may be made in the construction and arrangement of the several parts without departing from the spirit of the invention.

In the drawings:—Figure 1, is a front view of the device, showing the same installed in the fire box of a locomotive. Fig. 2, is a side elevation of the same. Fig. 3, is a top plan view of the same. Fig. 4, is a detail vertical sectional view of the nozzle, and illustrates the method of securing the same to the rear wall of the fire box.

Referring to the drawings, my device comprises a double walled air nozzle 1, of iron or steel, or other suitable material, which is formed with the curved discharge end 2, having an elongated discharge opening 3, therein of the proper form to properly distribute the air throughout the fire box. Said air nozzle 1, is also formed with the hollow bosses 4, extending at right angles from the rear thereof; and the ducts 5, in said bosses 4, communicating with the water chamber 6, formed by the double walls of said nozzle 1. Said air nozzles 1, are preferably placed in the two rear corners of the fire box 7, and are shown as attached thereto in the following way; although they may be secured in any suitable manner. The rear wall of the fire box 7, comprises the plates 8, and 9, which are spaced apart and form the water leg 10; while at suitable places, said plates 8, and 9, are pierced and joined by the tubes 11; and within said tubes 11, are inserted the bosses 4, of the air nozzle 1, which are held therein by the nut 12, threaded thereon and by this method of mounting the air nozzle 1, no provision has to be made for expansion and contraction in the water pipes, as they are all without the fire box 7. Said bosses 4, are provided with the internal screw-threads 13, by which are secured the water pipes 14, which have their other ends tapped into the outer plate 8; and in this manner, a circulation of water is maintained through the water chamber or jacket 6, from the water leg 10, of the boiler; said water pipes 14, being supplied with the cut off valves 15, for the purpose of preventing the water entering the fire box, if one of the air nozzles 1, should become broken. There is also provided a flushing valve 16, placed in the lower pipe 14, be-

tween the valve 15, and the nozzle 1, for the purpose of cleaning out said water chamber 6.

The lower end 17, of the air nozzle 1, is 5 reduced in diameter below the lower end of the water chamber 6, and extends downward through the grate 18, and is connected by a T-fitting 19, to an air pipe 20; said air pipe 20, connects together both of the 10 air nozzles 1, and has secured to each end, a curved intake air pipe 21, which extends from the side of the locomotive, and is fitted with a netted intake funnel 22, on the 15 end thereof, in such a manner, that while the locomotive is in motion, sufficient air will enter the intake funnels 22, to discharge from the nozzles 1, into the fire box; the air being heated as it passes through the nozzles 1, by the heat therefrom. To 20 produce the same result and supply the air for the nozzles, while the locomotive is standing still, an air pipe 23, is attached to the air pipe 20, running from the usual force draft pipe from the power blower 25 (not shown). Also for starting a circula-

tion of air through the nozzle 1, a steam jet pipe 24, is attached to the T-fittings 19; the admission of steam being controlled by a valve 25.

Having thus described my invention what 30 I claim as new and desire to secure by Letters Patent is:—

In a smoke consumer of the class described, the combination with a fire box having a water-leg, and air inlet and supply 35 pipes leading to said fire box, and an air discharge nozzle mounted in said fire box and connected to said air supply pipes, said air discharge nozzle formed with a water jacket, of hollow bosses integral with and 40 extending from said air discharge nozzle through the wall of said fire box, and means for connecting said hollow bosses to the water leg of said fire box.

In testimony whereof I affix my signature in presence of two witnesses.

HARRY B. ROWE.
